UNITED STATES PATENT OFFICE

2,405,369

SAFETY KEY CABINET

Charles I. Poulsen and Henry F. Rose,
Akron, Ohio

Application May 26, 1945, Serial No. 595,956

1 Claim. (CL 312—189)

1

This invention relates to a safety device for the protection of automobile or other keys and has for an object to provide a cabinet for keys from which the keys cannot be removed by unauthorized persons.

Another object of the invention is to provide a cabinet for a large number of keys and means whereby the keys may be collectively locked or released.

A further object of this invention is to provide the combination of a cabinet with keys attached to chains which may be safely held against unauthorized removal, and exposed means on each key chain for indicating the person or car to whom or which the key belongs.

Other features and advantages will become more readily apparent from the following description and the accompanying illustrative drawings in which:

Figure 1 is a plan view of our safety key cabinet,

Figure 2 is a similar view partly broken away and showing certain parts in adjusted position,

Figure 3 is a sectional view taken on line 3—3 of Figure 2,

Figure 4 is a similar view taken on line 4—4 of Figure 1,

Figure 5 is a sectional view taken along the line 5—5 of Figure 2, and

Figure 6 is a broken away detail of a lock member.

In the accompanying drawings as above enumerated and in the following specification, like characters of reference indicate like parts throughout and in which 10, refers to our safety key cabinet which consists of a box 11, of any desired shape or size depending upon the number of keys to be held, or the place it is to be located. This box is closed with fixedly secured walls 12, etc., on all sides. The top or face walls 13, being provided with columns of spaced bores 14, 15, etc., extending therethrough, from which extend slots 16, terminating in transverse T-slots or grooved recesses 17.

Slidably mounted upon tracks 18 and 19, is a lock plate 20, which is held against the under surface 21, of the face wall 13, by said tracks. This plate 20, is provided with bores 22, of the same diameter as that of the bores 14, and extending slots 23, of the same dimensions as that of the slots 16. The side 24, of said plate 20, has attached centrally thereto a push member 25, the edge 26, of which projects beyond the edge 27, of plate 20.

The wall 12', of the cabinet 11, is provided

2

with a door 28, hinged at 29, to swing outwardly only and away from the wall 13, and against the edge 30, of which the edge 26, of member 25, is held, by means of springs 31 and 32, the ends 33, of which are connected to the eyes 34, secured to the under side 34, of plate 20. The ends 36, of the springs are connected to eyes 37, on the upper part of the inner side 28, of the wall 12', whereby when the door is pulled outwardly by its knob 39, the said springs 31 and 32, will draw the plate 20, outwardly until the edge 27, thereof abuts the flange or stop 40, depending from the edge 41, of wall 13. In this position the bores 22 and 14, and the slots 23 and 16, exactly align, as indicated in Figure 4 of the drawings, and in which position a key 42, and chain 43, may be dropped through the openings into the box and be held suspended therein by the tag 44, having indicia 45, thereon indicating the car or person to which it belongs. This tag 44, must be of somewhat greater diameter than the said bores 22 and 14, so that it cannot pass said bores.

After the key or keys are inserted the door 28, is closed causing it to push member 25 (which was projected outwardly of the door opening, when the plate 20, moved outwardly) back into the cabinet and with it moving said plate 20, inwardly against tension of said springs. This action causes the bores 22, to move out of alignment with bores 14, and at the same time shoves the key chains 43, to the rear ends of the slots 16, causing the edges 46, of the tags 44, to drop into grooves 47, whereby they will be held in vertical position, through the weight of the chain and key, and whereby the indicia on the tags may be easily read. This latter relative position of the plate 20, and wall 13, is clearly indicated in Figures 2 and 3 of the drawings, and locks the keys within the cabinet. A latch 47, is provided on the edge 48, of the door which latch is controlled by a lock 49, whereby the cabinet may be secured against unauthorized persons.

Links may be substituted for the springs 31 and 32, and attached to the door in which case the plate 20, will be actuated in both directions by the opening and closing of the door, and which will also obviate manual holding of the door and plate 20, against the tension of the springs and in this case the member 25, may be eliminated.

It is thought that persons skilled in the art to which the invention relates will be able to obtain a clear understanding of the invention after considering the description in connection with the

drawings. Therefore, a more lengthy description is regarded as unnecessary.

Minor changes in shape, size and rearrangement of details and parts such as come within the purview of the invention claimed may be resorted to, in actual practice, if desired.

Having now described our invention that which we claim as new and desire to procure by Letters Patent is:

A cabinet for holding keys with attached chains and identification disks comprising a receptacle having four interconnected sides, a bottom and a top, said top being formed with apertures having T-shaped extensions through which keys may be dropped, guide rails on the inner

walls of the opposite side of said receptacle, a locking plate formed with identical shaped apertures to those in said top adapted to slide on said guide rails, a closure member hinged to the front side of said receptacle, springs secured between said closure and said plate, and a push member attached to said plate adapted to extend beyond the lateral limits of said receptacle when the closure is open to align said apertures and to be engaged by said closure member to push said plate into its innermost position as the closure is closed to disalign said apertures thereby locking the keys in said receptacle.

CHARLES I. POULSEN.
HENRY F. ROSE.
